Primary Examiner — Joseph Kukella*Assistant Examiner* — Lavon M. Amerson(74) *Attorney, Agent, or Firm* — RatnerPrestia(57) **CLAIM**

The ornamental design for a seatbelt guide for vehicle, as shown and described.

DESCRIPTION

FIG. 1 is a perspective view of a seatbelt guide for vehicle showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The portions of the seatbelt guide for vehicle shown in broken lines are for illustrative and environmental purposes and form no part of the claimed design.
